UNITED STATES PATENT OFFICE

111,158

DESIGN FOR A COMBINATION REFRIGERATOR AND SERVING TABLE

Arthur P. Schulz, Michigan City, Ind., assignor to G. & J. Teller, Chicago, Ill., a partnership consisting of Grace Teller and Jacob Teller

Application January 8, 1938, Serial No. 74,142

Term of patent 14 years

To all whom it may concern:

Be it known that I, Arthur P. Schulz, a citizen of the United States, residing at Michigan City, in the county of La Porte and State of Indiana, have invented a new, original, and ornamental Design for a Combination Refrigerator and Serving Table, of which the following is a specification, reference being had to the accompanying drawing, forming a part thereof.

bination refrigerator and serving table, with the front door of the refrigerator in closed position.

Figure 2 is a similar view thereof, on a reduced scale with the front door of the refrigerator in opened position.

I claim:

The ornamental design for a combination refrigerator and serving table, as shown.

ARTHUR P. SCHULZ.
